(57) **CLAIM**

The ornamental design for a portion of a spark plug body, as shown and described.

DESCRIPTION

FIG. 1 is a perspective view of a portion of a spark plug body according to the first embodiment of the present invention. FIG. 2 is a front elevational view of the portion of a spark plug body according to the first embodiment of the present invention.

FIG. 3 is a left side elevational view of the portion of a spark plug body according to the first embodiment of the present invention.

FIG. 4 is a bottom plan view of the portion of a spark plug body according to the first embodiment of the present invention.

FIG. 5 is a top plan view of the portion of a spark plug body according to the first embodiment of the present invention. The rear elevational view according to the first embodiment of the present invention is identical to the front elevational view shown in FIG. 2, and the right side elevational according to the first embodiment of the present invention view is the same as the left side elevational view shown in FIG. 3. The broken lines in FIGS. 1-5 are included for the purpose of illustrating portions of the spark plug that form no part of the first embodiment.

FIG. 6 is a perspective view of a portion of a spark plug body according to the second embodiment of the present invention.

FIG. 7 is a front elevational view of the portion of a spark plug body according to the second embodiment of the present invention.

FIG. 8 is a left side elevational view of a portion of a spark plug body according to the second embodiment of the present invention.

FIG. 9 is a bottom plan view of the portion of a spark plug body according to the second embodiment of the present invention; and,

FIG. 10 is a top plan view of the portion of a spark plug body according to the second embodiment of the present invention.

The rear elevational view according to the second embodiment of the present invention is identical to the front elevational view shown in FIG. 7, and the right side elevational according to the second embodiment of the present invention view is the same as the left side elevational view shown in FIG. 8.

The broken lines in FIGS. 6-10 are included for the purpose of illustrating portions of the spark plug that form no part of the second embodiment.
